HARD SURFACE FLOOR COVERING OR SIMILAR ARTICLE

Alfred H. Bergen, Trenton, N. J., and Joseph F. Dobry,
Langhorne, Pa.

Application December 18, 1956, Serial No. 44,248

Term of patent 14 years

(Cl. D92—17)

The drawing is a plan view of a hard surface floor covering or similar article showing a full repeating unit in the area bounded by the left and bottom margins and the dashed lines.

We claim:

The ornamental design for a hard surface floor covering or similar article, substantially as shown and described.
